PACKING DEVICE FOR DRILL RODS

Filed Sept. 14, 1923

Fig. 1.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

PACKING DEVICE FOR DRILL RODS.

Application filed September 14, 1923. Serial No. 662,746.

To all whom it may concern:

Be it known that I, CHARLES C. HANSEN, a citizen of the United States, and a resident of Easton, county of Northampton, State of Pennsylvania, have invented a certain Packing Device for Drill Rods, of which the following is a specification accompanied by drawings.

This invention relates to well drills and more particularly to drills of the rotary type having a cutting bit attached to a rotary spindle or drill rod, such, for instance, as a core drill.

In drilling oil and other wells, gas pressures of considerable magnitude are frequently encountered when a certain depth has been reached. Uncontrolled escape of such gas presents a danger on account of the damage likely to be done to persons and the equipment, as well as because of the impossibility of carrying on the drilling operation. Various means have therefore been employed to pack the well against unintentional escape of the gas during the drilling as well as during the raising and lowering of the drill rods and drilling tools, but it has heretofore been difficult to satisfactorily prevent the escape of gas from a well in which a core drill of the type mentioned above was being used. This is partly due to the fact that outside coupled drill rods are usually employed, the couplings being of larger diameter than the rods, so that any satisfactory packing for such drill rods must provide for a tight closure at all times in spite of the difference in the diameter of the drill rod.

The primary object of the present invention is to effect substantially pressure tight sealing of the well around the drill rod and to tightly pack the drill rod at all times so that passage of portions of the drill rod of different diameter past the seal may take place in either direction without permitting the gas under pressure to escape. A further object is to effect automatic adjustment of the packing members to accommodate the portions of the drill rod of different diameter.

Still further objects will hereinafter appear, and to the ends set forth the invention consists in the several features of construction and operation set forth in the following specification and shown in one preferred

embodiment in the annexed drawing, forming a part hereof, in which—

Figure 1 is a vertical sectional view, partly broken away, of a typical core drill outfit in place in a well being drilled, showing the invention applied thereto.

Figure 2 is a detail side view taken in a direction opposite to Figure 1 and partly in section showing the automatic mechanism for adjusting the packing rollers;

Figure 3 is a detail transverse sectional view taken on the line 3—3 of Figure 2 looking in the direction of the arrows, and

Figure 4 is an enlarged perspective view of one of the packing rollers.

The drawings show, diagrammatically, an oil well of considerable depth, which may be from 1000 to 2500 feet or more. The first or outer casing A usually extends to a depth of from 800 to 2000 feet and is tightly embedded at its lower end B. The inner casing D extends below the outer casing A substantially to the bottom of the well. The rotary drill rod or spindle composed of the rod sections E connected by outside couplings F extends through the casing A, and the core barrel having the bit G is connected to the lowermost rod section E. The drill spindle is rotated in the usual manner and the drilling is continued with the bit G until the gas strata H has been reached where the gas encountered may be under any pressure up to from 1500 to 2000 pounds per square inch. Means are provided in the working chamber C for sealing the inner casing D and preventing unintentional escape of the gas. In this instance a pair of co-operating packing rollers J and J' are suitably mounted within a packing box K around the drill rod in position to embrace the drill rod upon opposite sides and constitute an effective seal. The packing rollers J and J' are designed to pack the drill rod and prevent leakage during passage of either the smaller diameter rod sections E or larger diameter couplings F between the rollers J and J'.

A gate valve casing L and a pressure bleeder valve connection O are preferably interposed between the packing box K having the cover K' and the inner well casing D, and a relief valve connection P is preferably superposed above the packing box K. The valve connection P, packing box K, and

valve casing L and connection O are concentrically arranged about the drill rod within the working chamber C, and securely bolted together. The pressure bleeder valve connection O is suitably secured to the top of the inner casing D, as by the screw threaded flange Q. The top of the relief valve connection P is closed by a circular end plate R having a central aperture S, the diameter 5 of which aperture S is such as to enable the drill rod coupling F to pass through. A disk T of rubber or other suitable compressible material is interposed between the plate R and section P. This disk T has an 10 opening U concentric with the aperture S but of slightly less diameter, so that a relatively tight fit is provided about the larger and smaller diameter portions of the drill rod during their movement into and out of 15 the well casing.

The pressure breeder valve O' is designed to permit a controlled flow of gas to escape from the well when desired. The gate valve L' enables the well casing to be tightly sealed up after removal of the drill rods and other tools from the well. The compressible disk T tends to prevent the escape of any gas which may leak past the seal formed by the packing rollers J and J' and 20 the relief valve P' permits the safe controlled removal of such gas.

The packing rollers J and J' are identical in construction and have peripheral semi-circular grooves V of relatively large 35 depth formed on opposite sides of portions W, which project slightly above the bases of the grooves V. Grooves X of lesser depth are formed in the faces of the projecting portions W. The grooves V and X 40 of the opposing rollers J and J' are adapted to be aligned with each other to form substantially circular openings corresponding to the different diameter portions of the drill rod. The grooves X embrace opposite sides of the drill rod sections E when 45 the rollers are in one position as shown in Figure 1, and the grooves V embrace opposite sides of the couplings F when the rollers are turned in either direction upon 50 their axles Y trunnioned in the walls Z of the packing box K.

The normal position of the packing rollers J and J' is with the grooves X of the respective rollers embracing the sides of the 55 drill rod E. When the drill rod is lowered the projecting end a of the coupling F will engage the sides b of the projecting portions W of the rollers and cause the rollers to be rotated slightly, through an angle 60 which in the present instance is slightly less than 60° but which in all cases will depend upon the proportions of the parts. This rotative movement of the rollers will bring one set of grooves V into engagement with 65 the sides of the coupling F just before the

grooves X leave the sides of the drill rod. The seal is thus maintained at all times. When the drill rod is raised the opposite end c of the coupling F will engage the sides d of the portion W so that the opposite set of grooves V will embrace the coupling. The rollers J and J' are preferably balanced so that when the drill rod is raised or lowered and one of the larger diameter couplings F has passed through the seal the rollers will automatically return to normal position with the grooves X in embracing engagement with the smaller diameter drill rod section E. Any suitable means may be employed for this purpose.

In the present instance the rollers are balanced by oppositely acting resilient means in the form of semi-circular coiled springs e and f housed in a suitable retaining box g which may form part of the packing box 85 K. These springs e and f act upon a lever h connected to the axle Y of the roller J', and the movement is caused to be transmitted to the opposite roller J through the agency of intermeshing gears j and j' secured on the axles Y, so that the rollers act in unison. When the drill rod is in position so that the grooves X embrace the drill rod section E the rollers are balanced by the springs e and f. When the drill rod is lowered it will be against the spring f, so that this spring f will be compressed. As soon as the coupling F leaves the grooves V 90 one of the springs will be released and will act to return the rollers to normal position. The action of the springs will be reversed when a coupling F is passed through the seal in an upward direction, but the same effect will be produced.

Filler pieces k and k' are held by top 105 bolts o in the walls of the packing box K and fill out the circular groove X and are provided for the purpose of cutting off or sealing the gas on the outer sides of the packing rollers.

I claim:

1. A packing device for drill rods, comprising a well casing and a drill rod adapted to operate therein, portions of said drill rod being of different diameters, and co-operating packing members having a plurality of grooves, corresponding substantially to the portions of the drill rod of different diameters, whereby the packing members alternately embrace the said drill rod portions of different diameter and effect substantial sealing of the well casing.

2. In combination with a well casing and a drill rod having portions of different diameters, a pair of members each having peripheral grooves of different depth and adapted to cooperate to alternately embrace the said drill rod portions of different diameters, and automatic means for normally retaining said members in engagement with 130

a portion of one diameter of the drill rod, permitting movement of said members into engagement with another portion of different diameter and acting to restore said members to normal position as said other portion of different diameter passes out of engagement with said members.

3. A packing device for drill rods, comprising a well casing and a drill rod adapted to operate therein, said drill rod being composed of a plurality of separate sections with couplings between the sections of different diameters than the sections, and cooperating packing rollers having peripheral grooves of different depth adapted to alternately embrace the drill rod sections and couplings to substantially seal the well casing.

4. A packing device for drill rods, comprising a well casing and a drill rod adapted to operate therein, said drill rod being composed of a plurality of separate sections with couplings between the sections of different diameters than the sections, and cooperating packing rollers having peripheral grooves of different depth adapted to alternately embrace the drill rod sections and couplings to substantially seal the well casing, and automatic means for effecting movement of the rollers to cause one set of grooves to engage one portion of the drill rod of one diameter as another portion of different diameter passes its corresponding set of grooves.

5. A packing device for drill rods comprising a well casing and a drill rod adapted to operate therein, said drill rod being

composed of a plurality of separate sections with couplings between the sections of larger diameter than the sections and a pair of cooperating packing rollers having grooves of different depth adapted to embrace opposite portions of said drill rod sections, the openings between the grooves of said rollers corresponding substantially to the portions of different diameter of said sections and couplings, and effect substantial sealing of the well casing during passage of the drill rod between said rollers.

6. A packing device for drill rods, comprising a well casing and a drill rod adapted to operate therein, said drill rod being composed of a plurality of separate sections with couplings between the sections of larger diameter than the sections and a pair of cooperating packing rollers having grooves of different depth adapted to embrace opposite portions of said drill rod sections, the openings formed by the grooves of said rollers corresponding substantially to the portions of different diameter of said drill rod sections and couplings and effect substantial sealing of the well casing during passage of the drill rod between said rollers and automatic means for effecting movement of the rollers to cause one set of grooves to engage a portion of one diameter of the drill rod as another portion of different diameter passes its corresponding set of grooves.

In testimony whereof I have signed this specification.

CHARLES C. HANSEN.
